(57) CLAIM

I claim the ornamental design for an emergency notification device, as shown and described.

DESCRIPTION

FIG. 1 is a front view of the emergency notification device.
 FIG. 2 is a rear view of the claimed design.
 FIG. 3 is a right side view of the claimed design.
 FIG. 4 is a left side view of the claimed design.
 FIG. 5 is a top view of the claimed design.
 FIG. 6 is a bottom view of the claimed design; and,
 FIG. 7 is a perspective view of the claimed design.
 The broken lines appearing on FIG. 1 and FIG. 7 of "Lift then pull handle" and "Pull for Police" are environmental matter forming no part of the claimed design.
